UNITED STATES PATENT OFFICE.

HERBERT J. BREEZE, OF OLEAN, NEW YORK.

EMBALMING APPARATUS.

SPECIFICATION forming part of Letters Patent No. 487,244, dated December 6, 1892.

Application filed March 4, 1891. Serial No. 383,735. (No model.)

To all whom it may concern:

Be it known that I, HERBERT J. BREEZE, a citizen of the United States, residing at Olean, in the county of Cattaraugus and State of New York, have invented certain new and useful Improvements in Embalming Apparatus; and I do hereby declare the following to be a full, clear, and exact description of the invention, such as will enable others skilled in the art to which it appertains to make and use the same.

My invention consists in a new and improved aspirator and injector or embalming apparatus by the use of which the decomposed fluids and gases can be first drawn from the abdominal and other cavities, and the said cavities and the arteries and veins can then be filled with an antiseptic fluid; and the invention will be hereinafter fully described and claimed.

The accompanying drawing shows a side view of my complete apparatus, partly in section.

Referring to the several parts by their designating-numerals, 1 indicates a glass bottle of ordinary construction, the mouth of which is closed by a rubber stopper 2, which is formed with three longitudinal openings. Through one of these openings passes a hard-rubber tube 3, to the upper end of which is connected by a pipe 4^a the bulb 4, which forms the elastic air chamber or reservoir.

5 indicates a hard-rubber tube which passes through one of the stopper - openings and which is formed at its upper end with two branches 5^a 5^b. To the tube 5^a is connected by a pipe 6 an air-injector 7, consisting of a flexible bulb having the inlet and outlet valves 8 9, respectively, so that when the bulb is compressed air will be forced through the valve 9 and pipe 6, while when the grasp on the bulb is released the end valve 8 will open and the air rush in to fill the bulb. At the inner end of the air-injector 7 is arranged a cut-off valve 10, for the purpose hereinafter specified. To the branch tube 5^b is connected by a pipe 11 a flexible bulb 12, the valve 13 at the inner end of which opens toward the bulb 12, while its outer-end valve 14 opens outward, so that when this bulb is compressed the air from the bottle will pass the valve 13

and pass out through the end valve 14, and the air in the bottle 1 be thus exhausted. The exhaust-bulb is provided at its inner end with a suitable cut-off valve, as 15. Through the central opening of the stopper passes a hard-rubber tube 16, which is detachably connected at its lower end with an extension or hard-rubber tube 16^a. This latter tube is formed near its lower end with an entrance port or opening 17 and is provided with the gravitating float-valve 18, the operation of which will be hereinafter described.

To the upper end of the hard-rubber tube 16 is connected a flexible tube 19 of sufficient length and diameter, this tube being used both in withdrawing the decomposed fluids and gases from the abdominal and other cavities and also in filling the said cavities, veins, and arteries with an antiseptic fluid. In the outer end of this flexible tube is secured a hollow needle 20. Near its outer end the tube 19 is provided with a cut-off valve 21.

In the great majority of cases when about to embalm a body it is found necessary to first remove the decomposed fluids and gases, and this I accomplish with my invention in the following manner: The rubber stopper 2 is placed in the mouth of an empty bottle of any preferred size, the lower tube 16^a being first disconnected from the tube 16 and removed. The long hollow needle 20 is inserted into the abdominal cavities, and the cut-off valve 21 is closed. By then closing the cut-off valve of the injector-bulb 7 and opening the valve 15 and compressing the bulb 12 a number of times the air will be entirely exhausted from the bottle, and the vacuum thus caused will create a suction which when the valve 21 is opened will draw the decomposed fluids and gases from said cavities through the tube 19 into the bottle until the bottle is filled, when the stopper can be removed and the bottle emptied. The stopper is then replaced and the operation repeated until all decomposed fluids have been removed. The fluid contents of the arteries and veins is removed in the same manner. When the body has been thus prepared for the reception of the antiseptic fluid, the stopper 2 is placed in a bottle filled with such fluid, the extension 16^a being previously connected to the tube

16. The stop-valve 15 is then turned to cut off the exhaust-bulb 12 and the stop-valve 10 of the air-injector 7 is opened. The cut-off valve 21 is closed and the bulb 7 is compressed to force air through the pipe 6 into the upper part of the bottle and through the tube 4^a into the air chamber or reservoir 4, filling and distending the same, as shown in Fig. 1. When the air chamber or reservoir 4 has been filled 10 and the valve 18, by reason of its buoyancy, has opened the opening 17, the apparatus is ready for work as an injector, and the hollow needle 20 is then inserted in the body at the proper point for injecting the fluid into either 15 the abdominal cavities or the arteries. When the cut-off valve 21 is opened, the antiseptic fluid will, under the pressure of the air from the chamber or reservoir 4, flow slowly, evenly, and continuously into the arteries under a 20 uniform pressure, which will produce the best results in preserving the tissues and rendering the embalming most effective.

It is obvious that the branch tube 5 may be dispensed with and a plain straight tube, like 25 the tube 3, be substituted therefor, to which either of the bulbs 7 or 12 can be attached as they are required for use.

When the antiseptic fluid in the bottle is almost exhausted and reaches the level of the 30 opening 17 at the lower end of the tube 16^a, the valve 18, by reason of gravity, will close the opening 17, and thus prevent air from passing through the pipe 16^a and tube 19 into the arteries.

35 From the foregoing description, taken in connection with the accompanying drawing, the construction, operation, and advantages of my invention will be readily understood.

It will be seen that my embalming device 40 has two functions—first, that of removing all

decomposed fluids and gases from the abdominal and other cavities and the veins or arteries, and, second, that of injecting the antiseptic fluid into such parts—and that it is exceedingly convenient and effective for both 45 purposes.

Having thus described my invention, what I claim, and desire to secure by Letters Patent, is—

1. In an embalming apparatus, the combination of a suitable bottle 1, the stopper 2, formed with the three longitudinal openings, the tube 3, the storage-bulb 4, connected with the upper end of the same, the tube 16, the removable extension-tube 16^a, having the 50 opening 17 and the valve 18 at its lower end, the combined suction and injection tube 19, connected to the tube 16 and having the cut-off valve 21 and the hollow needle at its outer end, the tube 6, the injector-bulb 7, connected to the tube 5 and provided with the valves 8 and 9 and the cut-off valve 10, and the exhaust-bulb 12, connected to the tube 5 and provided with the valves 13 and 14 and the cut-off valve 15, substantially as set forth. 55

2. The combination of a suitable bottle 1, the stopper 2, formed with the three longitudinal openings, the tube 16, the tube 19, connected to the tube 16 and having the hollow needle at its outer end, a tube extending 70 through the third opening of the stopper, and the exhaust-bulb 12, connected to the said tube and provided with the valves 13 and 14, substantially as set forth.

In testimony whereof I affix my signature in 75 presence of two witnesses.

HERBERT J. BREEZE.
